UNITED STATES PATENT OFFICE.

RICHARD SHAW, OF MANCHESTER, ENGLAND, ASSIGNOR TO DE BERGUE & COMPANY LIMITED, OF MANCHESTER, ENGLAND.

METAL-PUNCHING MACHINE.

1,303,603.

Specification of Letters Patent.

Patented May 13, 1919.

Application filed December 5, 1917. Serial No. 205,598.

To all whom it may concern:

Be it known that I, RICHARD SHAW, a British subject, residing at Manchester, county of Lancaster, England, have invented certain new and useful Improvements in Metal-Punching Machines, of which the following is a specification.

The invention relates to metal punching machines in which the punches are mounted upon a vertically reciprocating punch head or beam and the dies on a fixed bed, two carriages or work holders with a traversing movement both longitudinally and transversely of the bed of the machine carry the work and a templet or guide is fitted to the side of the machine to enable a row of holes to be punched in the work parallel with its edge or according to a predetermined line or curve.

20 The invention is primarily designed for punching holes in ships' plates but may be applied to other long plates, sheets or strips of metal.

25 The invention consists essentially in connecting the two carriages or work holders by such mechanism or gearing as will give them a simultaneous transverse traverse to maintain contact of the edge of the work or a templet and a guide roller.

30 The invention will be fully described with reference to the accompanying drawings in which it is shown applied to a plate punching machine and in which sufficient of the machine is shown in outline to illustrate the invention.

35 Figure 1. is an elevation in outline of a punching machine designed for punching rows of holes in a plate parallel with the edge, (partly in section).

40 Fig. 2. is an outline plan of same.

Fig. 3. is an end elevation in outline.

45 Fig. 4. is an elevation in outline of a punching machine designed for punching rows of holes in a plate according to a predetermined curve, (partly in section).

Fig. 5. is an outline plan of same.

Fig. 6. is an end elevation in outline.

50 Fig. 7 is a top plan view of one extremity of the machine on an enlarged scale, particularly showing the one-work holding carriage and mechanism for operating the same.

Fig. 8 is a transverse vertical section on the line 8-8 of Fig. 7.

55 The longitudinal bed A, the vertically reciprocating punch head B, the punches b,

the die bed C, dies c, and the mechanism for operating the punch head are all of ordinary well known construction and the details are omitted from the drawings. The work carriages D, D' are also constructed, 60 mounted and traversed longitudinally of the machine in the ordinary way and by the ordinary mechanism which is also omitted from the drawings as its construction is well known and forms no part of 65 our invention.

According to our invention however, we connect the two work carriages by such mechanism as will cause their transverse traverse to be simultaneous.

70 The work carriage D is constructed in two parts d, d' the part d' traversing the longitudinal bed A and the part d to which the work is directly affixed or clamped traverses the part d' transversely and the work carriage D' at the other end of the machine is similarly constructed the part d² traversing the bed A and the part d³ to which the work is affixed or clamped traverses the part d² transversely.

75 The transverse traversing parts d and d³ of the work holders or carriages D, D' are each fitted with a rack E and the longitudinally traversing parts d', d² of the carriages each with a pinion e gearing with the rack, 80 the pinion operates the rack to move the carriage transversely in one direction and is rotated by the movement of the carriage when it is moved or forced back in the reverse direction. To the rack pinion e a 85 driving pinion e' is attached or connected so that the two pinions rotate together.

85 Each pinion e' gears with a pinion f on a shaft F carried in suitable bearings and extending longitudinally of the machine, the 90 pinions f being provided with keystraversing a slot in the shaft so as to rotate with the shaft.

95 On the shaft F a drum G is fitted with a band or chain g wound thereon from which a weight W is suspended. The weight W as it uncoils the band or chain g from the drum G rotates the shaft in one direction and as the shaft and drum are rotated in the reverse direction the band or chain g is rewound upon the drum. A spring may be 100 substituted for the weight.

105 Instead of the rack and pinion gearing the two carriages may be geared or connected together by gears and screws of coarse 110

pitch carried by one part of the carriage, and a nut of corresponding pitch carried on the transversely moving part of the carriage in place of the rack.

- 5 The traverse movement of the carriages and work may be controlled or directed by the edge of the plate or work P bearing against a guide roller or runner H mounted on the die bed C of the machine, as in Figs. 1 to 3, or the traverse movement of the carriages and work may be controlled by a guide roller or runner K mounted upon the traversing member d of one of the carriages D bearing against a templet M carried by brackets m affixed to the longitudinal bed A. The templet bar M may be straight or curved and may be set parallel to the edge of the plate or work P or at any inclination thereto as in Figs. 4 to 6. The longitudinal movement of the work carriage D' is obtained by the use of a screw K working in a nut along the side of the carriage, as clearly shown by Fig. 7. The screw K is driven from one moving part of the machine by bevel gears h', as shown particularly in Fig. 7, shaft H and gears h.

In operation the rotation of the shaft by the action of the weight W or a spring simultaneously traverses the two carriages 30 and the work thereon toward one side of the machine and maintains the edge of the work P constantly against a guide roller H as in Figs. 1 to 3, or the guide roller K constantly against the templet bar M as in Figs. 4 to 6 thereby punching a row of holes parallel with the edge of the plate P or parallel with the templet bar M the latter being set to any predetermined line or curve.

What I claim as my invention and desire 40 to protect by Letters Patent is:—

1. In a punching machine the combination with a longitudinal bed, a punch head carrying punches, a die bed with punch dies, and two separated work holder carriages, of 45 means for shifting the carriages transversely in straight lines and means for connecting the carriages to cause them to move unitedly and simultaneously to and fro in a transverse direction substantially as described.

Copies of this patent may be obtained for five cents each, by addressing the "Commissioner of Patents, Washington, D. C."

2. In a punching machine the combination 50 with the longitudinal bed, the punch head carrying punches, the die bed with punch dies, and two work holder carriages with longitudinal and transverse movements of a rack affixed to each transverse part of the carriage, pinions meshing with the racks, a longitudinal shaft extending the length of the machine, means for rotating the shaft and means for transmitting the motion thereof to the rack pinions and vice versa 55 from the rack to the shaft substantially as described.

3. In a punching machine the combination with the longitudinal bed, the punch head carrying punches, the die bed with punch dies, and two work holder carriages with longitudinal and transverse movements of a rack affixed to each transverse part of the carriage, pinions meshing with the racks, a longitudinal shaft extending the length of 70 the machine, a drum on the shaft, a band wound upon the drum, a weight suspended from the drum to rotate the shaft, a pinion through which the shaft passes and which slides over the shaft and gears to transmit 75 the motion of the shaft to the rack and carriage substantially as described.

4. A metal punching machine constructed with two work carrying carriages each formed of two parts one part traversing 80 longitudinally and the other part traversing transversely, a rack affixed to each of the transverse traversing parts of the carriages, pinions meshing with and to operate the racks, a single longitudinal shaft to connect 85 the two carriages, a weight and band to rotate the shaft, and gears to connect the shaft with the rack pinions to give a simultaneous transverse movement to the two carriages substantially as described. 90

In testimony whereof I have hereunto set my hand in presence of two subscribing witnesses, this 31st day of October, 1917.

RICHARD SHAW.
